(57) **CLAIM**

The ornamental design for a hanging rack connector for use in a bathroom, as shown and described.

DESCRIPTION

FIG. 1 is an upper perspective view of the hanging rack connector for use in a bathroom showing my design; FIG. 2 is a front elevational view thereof; FIG. 3 is a rear elevational view thereof; FIG. 4 is a side elevational view thereof; FIG. 5 is an opposite side elevational view thereof; FIG. 6 is a top plan view thereof; FIG. 7 is a bottom plan view thereof; and, FIG. 8 is a reduced perspective view thereof, with the broken-line disclosure of a second connector and towel bar being for illustrative purposes only and forming no part of the claimed design.
